UNITED STATES PATENT OFFICE.

THOMAS ELISHA WASHBURN, OF COALINGA, CALIFORNIA, ASSIGNOR OF ONE-HALF
TO EDGAR EARL WALTON, OF COALINGA, CALIFORNIA.

SELF-CLOSING VALVE.

Application filed December 30, 1922. Serial No. 610,017.

To all whom it may concern:

Be it known that I, THOMAS E. WASHBURN, a citizen of the United States, and a resident of Coalinga, in the county of Fresno and State of California, have invented certain new and useful Improvements in Self-Closing Valves, of which the following is a specification.

This invention relates to an automatic or self closing valve for use with oil or gas wells or the like, and it is designed to prevent the oil or gas from escaping from the well and getting beyond the control of the operators when the oil or gas strata is penetrated by the drill.

Accordingly, the invention consists in incorporating in the well casing a housing or valve casing in which is operatively mounted a valve normally opened but organized with a pressure responsive device so that when the oil or gas is struck and flows up through the casing it will actuate the pressure responsive device and cause the closing of the valve.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a view in elevation, showing the shell or housing in which the operative parts of the present invention are arranged;

Figure 2 is a fragmentary view in transverse vertical section through the shell or housing, parts being shown in elevation for the sake of illustration;

Figure 3 is a view in transverse section on line 3-3 of Figure 2;

Figure 4 is a similar view on line 4-4 of Figure 2;

Figure 5 is a similar view, on line 5-5 of Figure 2;

Figure 6 is a detail perspective view, showing one of the sections or slips of the valve assembly;

Figure 7 is a fragmentary perspective view, illustrating one of the guide ribs for the valve slips;

Figure 8 is a view in section; illustrating the construction of the offtake valve;

Figure 9 is a bottom plan view of the valve in open position, illustrating the cable guides, parts being shown in section and parts being omitted for the sake of illustration;

Figure 10 is a detail perspective view of the tool guide;

Figure 11 is a similar view of the cable guide; and

Figure 12 is a view, in elevation, of the manually operable closing device.

Referring to the drawings wherein for the sake of illustration is shown the preferred embodiment of the invention, the numeral 10 designates generally the shell or housing in which the operative parts of the present invention are arranged. This shell 10 includes a cylindrical portion 11 which has integrally formed with its upper end a frusto-conical portion 12 which in turn merges at its upper end into a neck 13 having threaded on its upper end the usual casing collar 14. The lower end of the cylindrical portion 11 of the shell has connected thereto a head or bottom section 15 having an upstanding annular flange 16 which is internally threaded for engagement with the external threads on the lower end of the cylindrical portion 11, as shown in Figure 2. Bolts 17 are also provided, and have threaded engagement with the flange 16 and the adjacent portion of the shell 10 to aid in securing the bottom section to the shell or casing. The bottom section 15 is provided with a depending reduced extension 18, the lower end of which is externally threaded as at 19 for connection with the collar or coupling of the well casing.

A valve designated generally at 20 is operatively arranged within the shell 10 and is made up of a plurality, preferably, six sections or slips, designated at 21. These slips 21 are of substantially the same construction and each includes a plate like body portion 22 of sector shape, and having formed integral therewith a depending guide wing 23, the outer surface of the guide wing 23 corresponding in formation to the inner surface of the frusto-conical portion 12 of the shell. In the assembly, the guide wings 23 slide against the inner surface of this portion 12 of the shell and the body portions 22 of the slips extend transversely across the interior of the shell. The adja-

cent lateral faces of the body portions 22 of the slips are formed with interfitting ribs and grooves designated at 24 and 25, respectively, so that when the valve is in 5 closed position that is when the slips are at their extreme upper position they will serve to completely obstruct the bore or passage through the shell. The inner or small ends of the body portions 22 of the valve slips 10 are cut away, as at 22^a in order to accommodate the cable C, as shown in Figure 2. The slips 21 also carry cable guides 26 in the form of arcuate fingers riveted or otherwise connected to the plates, the arcuate fingers 15 being arranged, as shown in Figure 11 and certain of the fingers being offset, as indicated at 27 so that these fingers will not interfere with each other or with the operation of the valve.

20 In order to constrain the slips to partake of their proper movements in the shell under cut or dove-tailed guides grooves 28 are formed in the slips and extend longitudinally thereof, the guide grooves flaring or 25 widening at their upper ends, as indicated at 29. These guide grooves 28 receive guide ribs 30 riveted, as at 31, to the shell 10, the guide ribs having under cut side faces 32 which coact with the under cut side walls of 30 the grooves of the slips and these guide ribs are also widened at their upper ends, as indicated at 33, so that the upward movement of the slips in the shell is limited.

35 A pressure responsive device is provided for controlling the valve 20 and may comprise a pair of spaced vanes or pressure plates 35 of annular form, the plates being held in spaced relation by pins or arms 36 and being mounted for sliding movement in 40 the cylindrical section 11 of the shell 10. This pressure responsive device is operatively connected with the valve 20 and in the embodiment shown connecting rods 37 are employed and are pivotally connected, as at 45 38 to the plates 35 and are also pivotally connected, as at 39, to the slips 21.

Within the shell 10 a number of vertically extending tool guides 40 are arranged. These tool guides 40 have lugs 41 at their 50 lower ends received in seats 42 provided therefor in the bottom section 15 and adjacent their ends the tool guides are bolted, as at 40^a to the frusto conical portion 12 of the shell. The portions of the tool guides 55 which extend through the cylindrical section 11 of the shell are of reduced size for the major portion of their length and these reduced portions of the tool guides operate in radial slots 43 provided therefor in the 60 plates 35 of the pressure responsive device so that these tool guides also serve as guides for the pressure responsive device.

In order to insure the actuation of the pressure responsive device the bottom section 15 is provided with a number of pockets

45 which underlie the lowermost plate 35 and which opens into the reduced extension 18 of the bottom section.

With the construction thus far described when the gas or oil bearing strata is penetrated by the drill, the oil or gas will rush up through the casing and will impinge against the plates 35 elevating these plates from the lower end to the upper end of the cylindrical section 11 of the shell. This motion of the plates is transmitted to the slips or valve sections through the connecting rods 37 so that these slips or valve sections ride up on their guides 30 and come into engagement with each other as shown in Figures 2 80 and 3 thereby completely obstructing the passage through the shell and preventing the oil or gas from flowing out of the well casing. In this manner the flow of oil or gas is arrested at the very beginning and thereby the possibility of any considerable body of oil or gas gaining momentum and escaping in a forcible and destructive manner is prevented, thus eliminating waste and possibility of damage.

At times in the drilling of wells intermittent puffing of gas is experienced, and in order to prevent this puffing of gas from closing the valve, means is provided for releasably maintaining or holding the pressure responsive device in the lower end of the shell 10. This means may comprise a rotatable bar 50 mounted in an opening 51 provided therefor in the bottom section 15. The upper end of the bar 50 has integrally formed therewith a laterally extending locking arm 52 which is adapted to be inserted through a slot 53 formed in the lowermost plate 35 and then turned so as to engage this plate 35 and consequently lock the pressure responsive device against actuation by the puffing above mentioned. The bar 50 also carries a beveled collar 54 which is ground so as to have sealing engagement with a seat 55 formed in the bottom section 15.

To provide for the manual closing of the valve when desired a tool is furnished with the equipment thus far described, this tool embodying a core or mandrel 58 having a beveled flange 59 at its lower end and having its upper portion threaded, as at 60. The beveled annular flange 59 is engageable with a seat 61 provided therefor in the slips of the valve assembly. A handle 62 is threaded into the upper end of the mandrel 58 and a hook 63 is threaded in the lower end thereof. The hook may be engaged with the pressure plates 35 and the elevator lifted up to closed position. In closed position the nut 65 threaded on the mandrel 58 is turned down to engage the top of the valve slips. This action of the nut together with the beveled flange 59 holds the slips in closed position.

In order to provide for the offtake of oil

or gas from the shell a valve 70 or a number of such valves are incorporated in the bottom section 15. As shown in Figure 8 the valve 70 includes a cylinder plug externally threaded, as at 71, and engaged with an opening provided therefor in the valve casting. This valve 70 has an axial bore 72 from which a radial bore 73 leads, the radial bore communicating with a passage 74 provided therefor in the bottom section 15 when the plug is in one position. The outer end of the plug is headed, as at 75, and the outer end of the bore 72 is internally threaded, as at 76, so that the plug may be coupled with a pipe or the like. The head 75 facilitates the turning of the plug so as to bring the radial bore into registration with the passage 74 so as to move this bore 73 out of registration with the passage 74 thus opening or closing the valve.

I claim:

1. A self-closing valve for use with oil or gas wells comprising in combination with the well casing, a valve housing incorporated in the well casing, a valve in said housing and a pressure responsive device operatively connected with the valve and adapted to be actuated to close the valve when gas or oil is struck, and manually operable locking means for holding the pressure responsive device against actuation when desired.

2. A self closing valve for use with oil or gas wells comprising in combination with the well casing, a valve housing incorporated in the well casing, a valve in said housing, and a pressure responsive device designed to be actuated solely by the oil and gas pressure within the housing and operatively connected with the valve so as to be actuated to close the valve when gas or oil is struck, said pressure responsive device including an annular pressure plate having its entire surface exposed at all times to the pressure of oil and gas existing within the housing.

3. A self closing valve for use with oil or gas wells and comprising, in combination with a well casing, a valve housing associated with the well casing and having a passage therethrough, a pressure operated valve designed to be actuated by the oil and gas pressure within the housing and comprising a plurality of sections, said sections being normally disposed so as to leave the passage through the valve housing entirely unobstructed and thus permit the passage of tools through the housing, said sections being also movable into engagement with each other to close the passage through the housing when oil or gas is struck, and a tool guide arranged within the housing.

4. In a device of the character described, a valve housing having a section of uniform diameter and a tapering section, a valve operating in the tapering section of said

valve housing and comprising a plurality of sections slidably mounted in the tapering section of the valve housing and adapted when disposed at the large end of the tapering section to leave a substantial and entirely unobstructed passage through the valve housing while completely obstructing passage through the valve housing when disposed at the small end of said tapering section and a pressure responsive device designed to be actuated by the oil and has pressure within the housing and arranged in the uniform section of the valve housing and operatively connected with the sections of the valve, said pressure responsive device including an annular pressure plate exposed to the oil and gas pressure within the housing.

5. A self closing valve for use with oil or gas wells comprising in combination with a well casing, a valve housing incorporated in the well casing, a valve in said valve housing comprising a plurality of sections, each including a horizontally disposed sector-shaped plate or body portion, and a depending guide wing, said sector-shaped plates being movable into engagement with each other to obstruct the passage through said valve housing or being movable out of engagement with each other to leave a substantial open and unobstructed passage through the valve housing, cooperating means between the valve housing and the wings of the valve sections for guiding said sections in their movements and a pressure responsive device arranged in said valve housing and operatively connected with the sections of the valve.

6. In a device of the character described, a valve including a plurality of sector-shaped plates and a pressure responsive device designed to be actuated by the oil and gas pressure within the housing and connected to the parts of the valve for closing the same when oil or gas is struck.

7. In a device of the character described, a valve including a plurality of horizontally disposed sector-shaped plates, said plates having horizontally disposed interfitting ribs and grooves.

8. A self closing valve for use with oil or gas wells comprising in combination with a well casing, a head connected thereto, a valve housing surmounting the head and including a cylindrical section and a frusto-conical section, a valve operating in the frusto-conical section, said valve being made up of a plurality of sections, each section including a sector-shaped plate and a depending guide wing slidably engaged with the wall of the frusto conical section, co-operating means between the guide ring and the frusto-conical section for constraining the sections of the valve to proper movement, the sector shaped plates of the valve

- being engaged with each other and obstructing the passage through the housing when the sections of the valve are moved to the small end of the frusto-conical section of 5 the housing while leaving a substantially open passage through the housing when disposed at the large end of said frusto-conical section and a pressure responsive device operatively connected with the sections 10 of the valve comprising a pair of spaced annular pressure plates operating in the cylindrical section of the valve housing, said head having pockets formed therein underlying the lowermost plate of the pressure 15 responsive device to insure the action of the pressure thereon.
9. A self closing valve for use with oil or gas wells comprising in combination with a well casing, a head connected with the 20 casing, a valve housing surmounting said head, a valve in said housing and comprising a plurality of sections, a pressure responsive device also arranged in said housing and comprising a pair of spaced annular 25 pressure plates operatively connected with the sections of the valve, a combined tool guide and pressure plate guide including a series of vertical guide strips secured to the head and to the valve housing, said pressure 30 plates having grooves accommodating said strips.
10. A self closing valve for use with oil or gas wells comprising in combination with the well casing, a valve housing incorporated 35 in the well casing, a pressure operated valve in said housing including a plurality of sections and cable guides comprising arcuate fingers carried by the sections of said valve.
- 40 11. A self closing valve for use with oil or gas wells comprising in combination with a well casing, a valve housing incorporated in the well casing, a valve in said housing including a plurality of sections, each section of the valve including a sector shaped 45 plate recessed at its inner end, a pressure responsive device operatively connected with the valve sections and adapted to be actuated by the pressure when gas or oil is struck, and means cooperable with the pressure responsive device for manually closing the valve when desired comprising a mandrel adapted to be accommodated by the recesses of the valve sections in the closed position of the flange, said mandrel having a 50 flange engageable with one side of said valve sections, a nut threaded on the mandrel and engageable on the other side of said valve sections, a hook carried by the mandrel and engageable with the pressure responsive device, and a handle carried by said mandrel.
12. A self closing valve for use with oil or gas wells comprising, in combination with a well casing, a valve housing incorporated in the casing, a valve in said housing and a pressure responsive device designed to be actuated solely by the gas and oil pressure within the housing and operatively connected with the valve so as to be actuated to close the valve when gas or oil is struck, 60 said pressure responsive device including a pair of annular pressure plates, the upper pressure plate having its entire surface exposed at all times to the pressure of the oil and gas existing within the housing, said 65 housing having pockets therein to admit the oil or gas pressure into the space below the lower pressure plate.
